UNITED STATES PATENT OFFICE.

WALTER S. NORTON, OF LUBBOCK, TEXAS.

ATTACHMENT FOR LATHES.

1,078,745.

Specification of Letters Patent. Patented Nov. 18, 1913.

Application filed September 4, 1912. Serial No. 718,556.

To all whom it may concern:

Be it known that I, WALTER S. NORTON, a citizen of the United States, residing at Lubbock, in the county of Lubbock and 5 State of Texas, have invented new and useful Improvements in Attachments for Lathes, of which the following is a specification.

My invention relates to attachments for 10 lathes, and especially to a cutting attachment for a jeweler's lathe.

One object of my invention is to provide an attachment having improved means whereby the cutting tool may be adjusted 15 to suit various conditions of use.

A further object of my invention is to provide a simple and efficient device of this kind, and one which may be manufactured and sold at a low cost.

20 The preferred embodiment of my invention is hereinafter described and illustrated in the accompanying drawings.

In these drawings: Figure 1 is an end view of the attachment. Fig. 2 is a side 25 elevation thereof. Fig. 3 is a transverse sectional view taken midway of the attachment and looking toward the angle bracket, the tool holder being removed. Fig. 4 is a plan view of the metal plate from which 30 the main bracket is formed, and, Fig. 5 is a perspective view of the main bracket.

Referring to the drawings, 1 as shown in Fig. 4 designates a plate of metal having 35 portions 2 thereof bent at right angles thereto to form end pieces or lugs 3, as shown in the other figures. Of said plate 1, 4 as shown in Fig. 4 designates a portion which is also adapted to be bent at right angles to the plate so as to provide an attaching plate 5, as shown in the other figures. Said plate 5 is provided with suitable means whereby it may be connected or attached to a jeweler's lathe. Said means as shown, consists of the metal of the part 5 being slit to provide a socket 6, which may 45 receive a suitable part of the lathe. The slit provides lugs 7 on opposite sides thereof, through which passes a suitable screw 8 adapted to clamp the same against the receiving portion of the lathe. After the end 50 pieces or lugs 2, and attaching plate 5 have been bent from the plate shown in Fig. 4, a side wall 9 is provided. In said side wall is provided an elongated slot designated 10.

55 The lugs 2 are provided with suitable aper-

tures in which is mounted to be turned, a screw rod 11 provided with a knurled head 12 by means of which the screw may be operated. Said screw is secured in the opening against displacement, by any suitable 60 means.

On the screw 11 is mounted by means of the screw threaded opening, an angle bracket 13, one arm of which terminates in a screw threaded shank 14 adapted to extend 65 through the elongated opening 10 and beyond the same to receive a knurled nut 15. The other arm of the angle bracket is provided with an opening through which passes a screw threaded shank 16, carried 70 by a tool holder 17. The shank 16 receives a clamping nut 18 beyond the bracket arm to which it is attached. Said tool holder is provided with a slot in which is removably secured a cutting tool such as 19, by means 75 of a set screw 20.

The device embodying my invention is principally adapted for use on jewelers' lathes and in connection with the recessing or cutting away of jewelry such as watch 80 plates to receive jewels or sets, or for the purpose of cutting recesses in wheels in watch plates. These of course, are only a few uses to which the tool may be put, it being obvious that it may be used for various purposes and that various forms of tools may be removably secured in the holder 17.

By means of the attachment of the angle bracket and supported tool holder and tool, 90 to the screw rod and in the elongated slot, turning movement of the angle bracket and attaching parts is prevented. The bracket and attaching holder and tool are slidable along the screw to accommodate the use of 95 the tool with work under various conditions, it being obvious that as the screw is turned, that the angle bracket will move along the same in a direction according to the direction in which the same is turning. It is 100 clear that screw threads on the screw 11 may be of any pitch desired so that any desired degree of adjustment or sliding of the angle bracket and supported tool, may be had.

It is clear that changes within the details of construction of my device may be made without departing from the spirit and scope of the appended claims.

Having thus fully described my said in- 110

vention, what I desire to secure by Letters Patent is:—

1. In a device of the class described, a bracket provided with a plurality of walls 5 arranged at an angle to each other and with lugs extending at an angle to said walls, one of said walls provided with an elongated slot, the other of said walls provided with attaching means, a screw rod mounted in 10 said lugs, a tool-supporting bracket mounted on said rod, and means on said latter bracket entering said slot.
2. In a device of the class described, a bracket having an elongated slot and provided 15 with a wall split to provide lugs and a socket between the lugs, a clamp member passing through said lugs, lugs arranged at an angle to said wall, a screw rod mounted in said latter lugs, a tool-supporting bracket mounted 20 on said rod, and means on said rod entering said slot.
3. In a device of the class described, a bracket provided with an elongated slot, attaching means provided on said bracket, a screw rod for said bracket, a tool-supporting bracket mounted on said rod, means on 25 said latter bracket extending through said slot provided with screw threads beyond the slot, and a nut engaging said screw threads.
4. In a device of the class described, a bracket having a wall and end pieces arranged at an angle to said wall, a screw rod mounted in said end pieces, attaching means provided on said bracket, said wall provided 30

with an elongated slot, a bracket, an angle 35 arm entering said slot and having another arm, and a tool supported from said another arm.

5. In a device of the class described, a bracket having a side wall provided with 40 an elongated slot, end pieces arranged at an angle to said wall, a screw rod mounted in said end pieces, attaching lugs provided on said bracket, clamping means for said lugs, an angle bracket mounted on said screw rod 45 provided with a portion extending through said elongated slot and receiving a nut beyond the slot, and a tool removably supported from the other arm of said angle bracket.

6. In a device of the class described, a 50 bracket having a side wall provided with an elongated slot, end pieces arranged at an angle to said wall, a plate portion split to provide lugs and a socket between the same, a clamp screw member passing through said 55 lugs, a screw rod mounted in said end pieces, an angle bracket mounted on said rod and having an arm extending through said elongated slot and provided with a nut beyond the slot, said bracket having another 60 arm, a tool holder, means to removably secure said holder to said another arm, a tool, and means to clamp said tool in said holder.

WALTER S. NORTON.
